UNITED STATES PATENT OFFICE.

RALPH H. DICK AND ALBIN G. BLOOMDAHL, OF MARIETTA, OHIO, ASSIGNORS TO THE
SAFE-CABINET CO., OF MARIETTA, OHIO, A CORPORATION OF OHIO.

HEAT-RESISTING CABINET.

1,252,790.

Specification of Letters Patent.

Patented Jan. 8, 1918.

Application filed December 31, 1913. Serial No. 809,622.

To all whom it may concern:

Be it known that we, RALPH H. DICK and ALBIN G. BLOOMDAHL, citizens of the United States, and residents of Marietta, Washington county, Ohio, have invented a new and useful Heat-Resisting Cabinet, of which the following is a specification.

Our invention relates to improvements in heat resisting cabinets and its principal object is to provide a simple device that can be constructed economically; which will have strength and complete rigidity, and which will be able to withstand a very high temperature, without serious damage to itself or injury or destruction to its contents.

In the device shown in previous patents, and in various structures hitherto placed upon the market, there have been certain defects and weaknesses which tended to reduce the efficiency of the structure in the matter of obstructing the entrance of heat to its interior and our invention has been especially devised to overcome such shortcomings.

We show in the structure of this application, a cabinet in which will be found a complete, integral outer shell of metal, on the inside of which sheets of insulating material are secured. Next to these sheets we place a much heavier block of insulating material, following which is a dead air space provided at all points where it approaches the surface of the outer wall of the cabinet or any openings therein, with insulating material which prevents the entrance of heat.

This dead air space lies between the block insulation and the inner walls of the cabinet which are also provided on one side with sheet insulation.

In the drawings herewith Figure 1 is a vertical section from the front to the back of the structure.

Fig. 2 is a vertical section from side to side of the structure on line 2—2 of Fig. 1.

Fig. 3 is a horizontal section.

Fig. 4 is a perspective view of the outer shell of the structure.

Fig. 5 is a slightly enlarged perspective view of the inner shell of the structure.

Fig. 6 is an enlarged view of the lower left corner of Fig. 3.

Fig. 7 is a diagrammatic view of the back wall of the inner shell showing the outline of the same in vertical cross section.

Fig. 8 is a diagrammatic view of the back wall of the inner shell showing the outline of the same in horizontal cross section.

Fig. 9 is a diagrammatic view of the back wall of the outer shell showing the outline of the same in vertical cross section.

Fig. 10 is a diagrammatic view of the back wall of the outer shell showing the outline of the same in horizontal cross section.

Fig. 11 is a diagrammatic view of the top wall of the inner shell showing the outline of the same in vertical cross section from side to side of the structure.

Fig. 12 is a diagrammatic view of the top wall of the inner shell showing the outline of the same in vertical cross section from the front to the back of the structure.

Fig. 13 is a diagrammatic view of the bottom wall of the inner shell showing the outline of the same in vertical cross section from side to side of the structure.

Fig. 14 is a diagrammatic view of the bottom wall of the inner shell showing the outline of the same in vertical cross section from the front to the back of the structure.

Fig. 15 is a diagrammatic view of one of the side walls of the inner shell showing the outline of the same in vertical cross section.

Fig. 16 is a diagrammatic view of one of the side walls of the inner shell showing the outline of the same in horizontal cross section.

In constructing our device an outer shell 21 as shown in Fig. 4, is formed, having a top 22, a bottom 23, and sides 24—24. 90 This outer shell can be formed from one sheet of steel or it can be made of two halves welded to form an integral frame open in the front and back. To close the back, a wall member 25, provided with peripheral U shaped flanges 26, may be formed and inserted through the front opening of the outer shell 21, and moved rearwardly therein until the flanges 26, engage with the rectangular flanges 27, on the rear of the 100

outer shell. These three thicknesses of metal may then be welded together or fastened in any suitable manner to form a tight joint.

This construction forms a very rigid and 5 tight frame and obviates the possibility of warping or buckling in the joint if a high degree of heat is encountered.

On the inside surface of the five walls 10 constituting the outer shell 21, sheets of insulating material 28, are secured in a suitable manner and a heavier block of insulating material 29, is used to furnish additional heat resisting means.

The inner shell 30, comprises a top 31, 15 a bottom 32, sides 33—33 and a back 34. The top member 31, as shown in Figs. 1, 2, 10, and 11, is composed of a sheet of metal having at its sides the flanges 35, at its front edge the flange 36, and at its rear 20 edge the flange 37. The bottom member 32, is provided at its side edges with the flanges 38, at its front edge with the flange 39, and at its rear edge with the flange 40.

The side members 33, are formed with 25 rectangular flanges 41—41 at the top and bottom and the flanges 42—42 on their rear and front edges.

The back member 34, is formed with the 30 rectangular flange 43, on every one of its four edges.

It will be seen that when the inner shell 30, is assembled, the flanges 43 on the back member 34, engage with the flange 40 on the bottom member, the flange 37 on the top 35 member and the flanges 42—42 on the side members 33.

The flanges 41—41 on the side members 33 engage respectively with the flanges 35 on the top member 31 and the flanges 38 40 on the bottom member.

We have found it advisable in practice 45 to weld together these various wall members after they are assembled for the purpose of obtaining as tight a joint as possible, and a practically integral structure. After assembling and welding, sheets of insulating material 44, are secured to the outer walls of the inner shell 30.

It is also practical to insert the walls of 50 which the inner shell is constructed, in the outer shell without assembling them outside, the inner top and bottom being positioned first, after which the side walls are inserted, and the inner back placed to hold all the 55 other members in their respective positions.

We also have found it desirable in some instances to construct the inner shell of three members instead of five by forming the top, back and bottom out of one sheet of 60 steel with hook flanges on the front and side edges of the top and bottom members. This member can then be inserted in the outer shell and the side walls provided with straight flanges on their top, bottom and

rear edges and with hook flanges on their 65 front edges can be positioned to complete the inner shell.

As shown in Fig. 2, we provide in the outer shell 21, support blocks 45, upon which the inner shell 30 rests when it is inserted 70 in the outer shell through the opening in the front. These support blocks may be made of sheet metal and run from the front to the rear of the outer shell of the cabinet. These blocks are stepped at their inner top 75 edges by recesses 46, and insulating strips 47 are preferably inserted against the vertical walls of said steps and insulating strips 47 are preferably laid flat on the horizontal portions thereof. The top and bottom sheets of the insulating material 44 may be placed in position before the insertion of the inner shell, and angular strips 48 of thin sheet metal are set in the steps to prevent 80 injury to said insulating material therein when the shell is slid into position.

This support block serves to position the inner shell with relation to the outer shell and being constructed of strong material it 90 also prevents injury to the walls of the outer shell by the weight of the inner shell. We employ it in the top of the cabinet, to prevent injury to the top wall of the outer shell in the event that the cabinet should be turned upside down during transportation 95 or at any other time.

As shown in Fig. 3 we have also devised a new form of tongue and groove construction 100 by means of which a very tight interlocking is obtained between the doors of the cabinet and the adjacent parts when the doors are closed. In devices of this nature it has always been a difficult matter to construct the said doors and adjacent parts so that the resistance to the entrance of heat 105 was equal to that found in the other parts of the cabinet. This is partly accounted for by the fact that in using a tongue and groove construction of the old type, sufficient space between the lines of the tongues and grooves had to be provided to permit a clearance when the door or doors are swinging and the tongues are entering or leaving the 110 grooves, and this space would thereby become a channel through which heat could enter the interior of the cabinet from the exterior.

Expansion, at high temperatures would 115 tend to separate the jambs and the door edges in view of the fact that the means by which the door or doors were locked would operate to hold said doors against bulging outwardly.

As shown in Fig. 3 this interlocking 120 tongue and groove construction comprises a side jamb formed of sheet metal, with a hook flange 49, at its inner edge engaging with the front hook flange 42, on the side

wall 33, of the inner shell. Grooves 50—50 with slightly curved walls are formed in the side jamb and the forward edge thereof consists of a straight flange 51, which inter-

terminates similarly in the flange 73 like- 65
wise held between the angle iron 52 and the lower front wall 74 of the outer shell 21.

We claim:

1. In a device of the character described the combination of a structurally independent inner shell provided with interlocking flanges, a structurally independent outer shell, intermediate members connected with the outer shell and having interlocking flanges which engage said flanges of the inner shell. 70

2. In a device of the character described the combination of a structurally independent inner shell comprising inner wall members provided with flanges, a structurally independent outer shell comprising a plurality of outer wall members, and intermediate members connected with the outer shell and provided with flanges which interlock with said flanges of the inner shell. 80

3. In a device of the character described the combination of a structurally independent inner shell provided with interlocking flanges, a structurally independent outer shell, intermediate members connected with the outer shell and having interlocking flanges which engage said flanges of the inner shell, said flanges being interlocked and welded together. 85

4. In a device of the character described 95 the combination of a structurally independent inner shell comprising a plurality of the inner walls of the structure and provided with flanges, a structurally independent outer shell comprising a plurality of the 100 outer walls of the structure, intermediate members connected with the outer shell and provided with interlocking flanges engaging said flanges of the inner shell forming an air space between said outer and inner shells, 105 and insulating material between said air space and said inner shell.

5. In a device of the character described 110 the combination of an outer shell open on one side, an inner shell open on one side, a door jamb connecting said shells and provided on its face which meets the hinged edge of the door with similar curved recesses and with an intermediate tongue between said recesses, and a door hinged to said jamb 115 and provided on its hinged edge with similar curved tongues and with an intermediate recess between said tongues, said tongues of the door engaging said recesses of the jamb and said intermediate tongue of the jamb 120 engaging said intermediate recess of the door when the door is closed.

6. In a safe cabinet the combination of an outer shell open on one side, an inner shell open on one side, a door jamb connecting said 125 shells and provided on each of its opposite sides with similar curved lateral recesses and with an intermediate tongue between said

5 fits between an angle iron 52, and the straight flange 53, on the outer shell. This angle iron 52, as shown, is placed inside of the front face of the outer shell 21, and gives strength and rigidity thereto.

10 The tongues 54, which serve to complete the interlocking construction referred to, are formed on a separate member and as can be seen in Fig. 3 have walls curved to fit snugly within the grooves 50, when the 15 doors of the cabinet are closed. Insulating material 55, may be used around the grooves 50, and in the tongues 54.

On the forward edge of the member provided with the tongues 54, a hook flange 56, 20 engages with a similar flange 57, on the outer wall of the door of the cabinet, and on the rear edge, hook flanges 59, and 60 lock together the inner door wall 61, and the tongue member.

25 It will thus be seen that this construction furnishes means by which any heat liable to enter at the hinge opening would be forced to take a most tortuous route to reach the interior of the cabinet and in addition would cause expansion of the walls of the tongue 30 54, and the grooves 50, so that a tight joint would be made.

Double doors are shown in the drawings herewith, swinging on the hinges 62, and 35 provided with outer walls 58, and the inner walls 61. The inner wall has the sheet insulation 61' and the outer wall is provided with sheet insulation 58' and the heavier block insulation 58².

40 In the center of the front of the cabinet where the inner edges 63 of the doors come together it will be seen that these edges are formed with a number of bends to form a tortuous heat resisting opening from the exterior to the interior of the cabinet.

45 The inner wall 61 of the door is provided at its upper and lower ends with hook flanges 64, which engage with similar flanges 65 65 at the inner edges of the top and bottom door moldings 66. These top and bottom moldings are bent to form horizontal grooves 66^a and horizontal ribs or tongues 66^b, which latter interfit with corresponding grooves 67 and 68 in the top and bottom 55 moldings of the door jambs. The inner edges of these jamb moldings are provided with hook flanges 69 and 70 respectively which engage the hook flanges 36 and 39 on the top and bottom walls of the inner shell.

60 The upper end of the top molding 67 terminates in a rectangular flange 71 positioned between the angle iron 52 and the upper front wall 72, of the outer shell 21; and the lower end of the bottom molding 68

- recesses, and a double door whereof the members are hinged to opposite sides of said jamb and each provided in its hinged edge with curved tongues and with an intermediate space between said tongues, said tongues of each door member engaging said recesses at one side of the jamb and said tongue of the same side engaging said intermediate recess of the door member when closed. 5
- 10 7. In a device of the character described, the combination of an outer shell open on one side, an inner shell open on one side, a door jamb connecting said shells and composed of sheet metal bent to form a recess in an elongated curve on one side of said jamb, the space between the walls of said recess being filled with insulating material, and a door hinged to said jamb and composed of sheet metal bent to form an elongated curved tongue provided with an insulating filling and adapted to enter said recess when the door is closed. 15
- 15 8. In a device of the character described, the combination of an outer shell open on one side, an inner shell open on one side, a
- 20
- 25
- door jamb connecting said shells and composed of sheet metal bent to form recesses in elongated curves on opposite sides of the jamb, the spaces between the walls of said recesses being filled with insulating material, and a double door whereof the members are hinged to opposite sides of said jamb and provided with curved tongues which enter said recesses when the door members are closed. 30
- 35 9. A device of the character described, comprising an outer shell open on one side, an inner shell open on one side and having hook flanges in its walls at said opening, and a door jamb connecting said shells and provided on its inner edge with hook flanges engaging said hook flanges of the walls. 40

In witness whereof we have hereunto signed our names this 17th day of December, 1913.
